UNITED STATES PATENT OFFICE.

CHARLES E. BRATT AND GEORGE FLUCK, OF SYRACUSE, NEW YORK, ASSIGNEES TO
CONTINENTAL CAN COMPANY, INC., OF SYRACUSE, NEW YORK, A CORPORATION
OF NEW YORK.

CAN-END-FEEDING DEVICE.

1,387,098.

Specification of Letters Patent.

Patented Aug. 9, 1921.

Application filed June 28, 1919. Serial No. 307,414.

To all whom it may concern:

Be it known that we, CHARLES E. BRATT and GEORGE FLUCK, citizens of the United States, residing, respectively, at Syracuse, 5 in the county of Onondaga, State of New York, have invented certain new and useful Improvements in Can-End-Feeding Devices, of which the following is a description, reference being had to the accompanying drawing, and to the figures of reference marked thereon.

The invention relates to new and useful improvements in can end feeding devices, and more particularly to a feeding device for 15 delivering can ends to the seaming station in a can closing machine.

An object of the invention is to provide a can end feeding mechanism of the above type wherein the can ends are conveyed one 20 at a time from a stack-holder to the seaming station and centered at the seaming station by a continuously rotating can end feeding member.

A further object of the invention is to 25 provide a can end feeding device of the above character with means for placing a can end in the path of movement of a can end feeding member, which means is controlled by the filled cans as they pass to the 30 closing machine.

A still further object of the invention is to provide a can end feeding mechanism of the above character with means for marking the can end as it is traveling from the stack-holder to the seaming station.

Another object of the invention is to provide a marking device which may be readily shifted for bringing into operation different marking dies.

These and other objects of the invention 40 will in part be obvious and will in part be hereinafter more fully disclosed.

In the drawings, which show by way of illustration one embodiment of the invention:—

Figure 1 is a plan view showing a part of a closing machine having the improvements applied thereto;

Fig. 2 is a sectional view on the line *a—a* 50 of Fig. 1;

Fig. 3 is an enlarged detail sectional view through the marking device showing a cover having an identifying mark impressed therein;

Fig. 4 is a sectional view on the line *b—b* 55 of Fig. 1;

Fig. 5 is a sectional view on the line *c—c* of Fig. 1;

Fig. 6 is a detail showing more or less 60 diagrammatically the assembled can end releasing mechanism;

Fig. 7 is an enlarged sectional view at the seaming station showing a can end as placed and centered by the can end feeding member;

Fig. 8 is a view showing more or less 65 diagrammatically and in front elevation the marking devices with a can end between the same;

Fig. 9 is a face view of one of the interlocking members in the train of mechanism for operating the marking devices; and

Fig. 10 is a similar view of the companion interlocking member.

In the patent to I. F. Warne, issued 75 March 16, 1915, No. 1,132,291, there is shown and described a feeding mechanism for a closing machine which is adapted to form a double seam between the can end and the flange on the can body. In this machine, 80 there is a centering ring directly beneath the seaming head having a tapered opening for centering the can body, and at the upper edge of this tapered opening there is a seat for the can end which temporarily supports 85 the can end centered relative to the can body so that said can end is placed on the can body by a relative movement of the can body and centering ring, after which the can end is joined to the body by a double seam. 90

The present invention is directed to an improvement in the can end feeding mechanism shown in this patent, and the invention resides broadly in the means for feeding the can ends from the stack-holder to the seat 95 above the tapered ring and centering the same relative to the opening formed by the tapered ring. The invention also resides in the means for releasing the can ends one at a time so that they may be taken by the conveying member to the seaming station, and the invention further resides in the marking means which is so constructed and arranged as to impress an identifying mark in the can end as it is traveling from the stack-holder to the seaming station without in any way retarding the movement of the can end. 100 Referring more in detail to the drawings,

the invention is shown as applied to a can closing machine which is provided with a supporting bracket 1 carried by the usual frame of the machine which is indicated 5 more or less diagrammatically in dotted lines in Fig. 1 of the drawings. This supporting bracket is formed with a tapered opening 2 for centering the can relative to the seaming head. Directly above said tapered opening is a seating ledge 3 for the can end, which seating ledge is so shaped as to center the can end directly about the center of the tapered opening 2. A can body is indicated in broken lines in Fig. 4 at C, and 10 the can ends are indicated in the drawings at c. At the upper face of the supporting bracket 1 is a cover plate 4 which is formed with a central opening 5 through which the can end and can body at the upper portion 15 thereof pass as they are presented to the seaming rolls. The construction of the centering ring and the seaming rolls, and the manner of operating the same, form no part 20 of the present invention and may be of a construction shown more in detail in the 25 Warne patent above referred to.

The can ends are stacked in a stack-holder indicated at 6 in the drawings. Said stack-holder is formed with a supporting base 7 30 which carries, as herein shown, four rods 8 between which the stacked can ends are placed. Mounted within the supporting base of the stack-holder are two slides 9 and 10. The slide 9 is provided with a pin carrying a roller 11, while the slide 10 is provided with a pin carrying a roller 12. Directly above the slides is a can end releasing ring 13 which is formed with an inclined slot 15, see dotted lines, Fig. 6, adapted to receive 40 the roller 11 which controls the slide 9. Said ring is also provided with an inclined slot 16 adapted to receive the roller 12. This ring 13 is adapted to be oscillated, and as it oscillates it will move the slides 9 and 10 toward and from the center of the stack-holder. Each slot is provided with a curved tapered 45 inner end indicated at 17 in the drawings.

When the parts are positioned as shown in Fig. 4, these tapered ends 17 project within 50 the stack-holder and the stacked can ends rest thereon. When, however, said slides are withdrawn, then the stack descends onto the supporting bracket 1 and the lowermost end will be seated in a can end race 18. After 55 the lowermost can end has been seated in said race, the slides are moved inwardly and the inner tapered ends thereof separate the lowermost end from the can ends directly above the same and raise the stack so as to 60 completely release this lowermost end. The can end race, as clearly shown in Fig. 7 of the drawings, extends from a point directly underneath the stack-holder to the can end seat at the seaming station. The can ends 65 are moved along the raceway therefor by

means of a rotating arm or member 19. Said can end moving arm or member is provided with a forward face 20 which is adapted to engage the can end and move the same along the race. In other words, this arm or 70 member 19 travels in a plane in which the race lies, and the extreme inner edge of the race is cut away to permit the movement of the arm with the inner end thereof projecting into the race. Mounted on the end of the 75 arm is a plate 21 which is adapted to overlie the edge of the can end and insure said can ends being held against the face of the arm or member which feeds the same forward. As the can end is moved along by the arm, 80 the tendency of the can end is to move outwardly away from the center of travel of the arm and this holds the can end against the outer end of the can end race.

The can end race is shaped so as to finally 85 bring the can end to the can end seat at the seaming station. This can end race is located in part concentric with the center of movement of the can end feeding arm or member 19 and in part eccentric thereto, so 90 that said can end gradually moves outwardly relative to said arm or member and finally the end of said member or arm passes by the can end. This occurs when the can end is fully located on the can end seat of 95 the seaming station and centered relative thereto. Said arm or member 19 is provided with a rounded nose 22 which aids in permitting the arm to pass the can end when finally seated, and the end of the arm insures the centering of the can end directly 100 above the center of the tapered opening 2.

The means for rotating the can end delivering arm or member 19 consists of the following elements: Mounted on the vertical 105 center shaft of the machine 22 is a gear 23 which meshes with a gear 24, and this gear 24 in turn meshes with a gear 25 which in turn meshes with a gear 26. The gear 26 is fixed to the lower end of a shaft 27 mounted 110 in suitable bearings 28 and 29 carried by the frame of the machine. At the upper end of the shaft 27 is a beveled gear 30 which meshes with a beveled gear 31 mounted on the end of a shaft 32. The shaft 32 is mounted 115 in suitable bearings 33 also carried by the frame of the machine. At the extreme outer end of the shaft 32 is a beveled gear 34 which meshes with a beveled gear 35 on a short vertical shaft 36. This shaft 36 is mounted in a 120 bearing 37 carried by the frame of the machine or the main supporting bracket 1. At the lower end of the shaft 36 is a sleeve 38 which is splined to the shaft 36 and rotates therewith. Said sleeve has an enlarged head 125 which serves as a means for supporting the feeding arm or member 19. Said member is secured thereto by suitable bolts 39. As the shaft 36 rotates, this arm or member 19 will rotate therewith. It will be noted that this 130

shaft 36 rotates continuously and, therefore, the arm or member feeding the can ends rotates continuously taking one end after another from the stack-holder, moving the can 5 end along the can end race therefor, and positioning the can end at the seaming station where the arm passes the can end and again comes underneath the stack-holder for picking up another can end and conveying the 10 same to the feeding station.

The means for releasing the can ends also operates continuously and consists of the following mechanism: Mounted on the shaft 36 is an eccentric 40 which is adapted to 15 operate with a sliding member 41. Said sliding member 41 is provided with a forked end 42 which straddles a pin 43, and this directs the reciprocating movement of the sliding member 41. A lever 44 is pivoted at 20 45 to the can end releasing ring 13. This lever at its other end is forked, as indicated at 44', and said forked end straddles a pin 46 which serves as a fulcrum pin for the lever. Mounted on the sliding member 41 is 25 a pin 47 which is spring-pressed up by means of a spring 48. Said spring in part surrounds a sleeve 49 projecting upwardly from the sliding member 41 and bears against a plate 50 fixed to the upper end of the pin 47. 30 The lower end of said pin has an enlarged head 51. When said pin is depressed, the head 51 extends down alongside of the lever 44 and serves as a means for connecting said lever to the sliding member 41. Said sliding 35 member has a shoulder 52 which is adapted to engage the other side of the lever 44. It will be readily seen that when the pin is lowered then the lever is held between said pin and shoulder and the vibrations movements of the sliding member through the 40 action of the eccentric 40 will be imparted to the lever 44, and this in turn will oscillate the ring 13 and move the slides 9 and 10 back and forth. If the pin 47 is released, then the 45 spring at once raises the same, and this releases the member 44 so that the sliding member 41 will force the lever over to the position shown in Fig. 6 where it will remain because there is nothing to return it when the 50 slide moves back.

The pin 47 is controlled by a train of devices which are operated upon by the filled cans as they pass through the machine. Located along the runway for the filled cans, 55 indicated in dotted lines at 53 in the drawings, is a pivoted arm 54. This arm is adapted to be engaged by a can and the can will move the arm rearwardly, as viewed in Fig. 1. When said arm is moved rearwardly, it 60 will swing the arm 55 carried by and depending from a shaft 56. This shaft 56 is mounted in suitable bearings in the machine and carries at its other end an arm 57 which extends outwardly and is connected to the pin 65 47 by means of a pivot pin 58. It will thus

be seen that when a can body passes through the machine and forces the arm 54 outwardly, it will swing the shaft 56 so as to depress the arm 57, and this will depress the pin 47 connected thereto and connect up the 70 lever 44 with the sliding member 41, and this in turn will cause a movement of the ring 13 and the releasing of the can end so that the can end will be brought around and centered on the can end seat just as the can body is 75 positioned underneath the tapered centering ring therefor. If, however, no can body passes by the arm 54, then the pin 47 is raised by the spring and no can end will be released from the stack. 80

Associated with the can end feeding mechanism is a marking means for impressing an identifying mark in the can end. Said marking means consists of two rotating marking disks 59 and 60. Each marking 85 wheel is provided with six dies, indicated at 61 in the drawings, see Fig. 8. These dies are arranged in pairs and each pair may be different so that any set of dies may be brought into operative position to impress 90 an identifying mark in the can end. The marking disk 59 is carried by a shaft 62, and the marking disk 60 is carried by a shaft 63. The shaft 62 carries a gear 64 meshing with a gear 65 so that these shafts 62 and 95 63 will always turn in the same timing and bring the marking dies into proper coöperative action to impress in the can end an identifying mark. The shaft 63 is provided with a beveled gear 66 which meshes with 100 a beveled gear 67. The beveled gear 67 is loosely mounted on the shaft 27. A disk 68 also loosely mounted on the shaft is bolted to the beveled gear and this disk forms one of two companion interlocking means for 105 securing the beveled gear to the shaft 27. The other interlocking member is in the form of a sleeve 69 and this sleeve is splined to the shaft so as to turn therewith. Said sleeve, however, may be moved endwise on 110 the shaft. The sleeve is formed with a face plate 70 which is provided with twelve radial grooves 71, see Fig. 9. The interlocking companion plate 66 is formed with two radially disposed lugs 72. These lugs 72 are 115 adapted to engage the grooves 71 in the face plate 70 of the sleeve 69. Said sleeve 69 is moved endwise by means of a fork 73 which is fixed to a shaft 74, and this shaft 74 is provided with a hand wheel 75 at its outer end which is readily accessible to the operator. By turning the hand wheel 75 the sleeve 69 may be slid on the shaft 27 so as to bring it out of mesh with the projecting lug 62 and thus the gear 67 is released from 120 the shaft 27. As soon as the shaft 27 is released, then the die carrying disks 59 and 60 may be rotated to bring another pair of coöperating dies into operation. It will be noted that the gear 67 is twice the size of the 125 130

gear 66 so that for one rotation of the gear 67 the gear 66 will receive two rotations. The can end feeding arm or member 19 rotates in timing with the shaft 27. As a result, when the dies come into contact with a can end, the tendency of the dies is to move the can end away from the arm or member 19 and thus prevents any possible damage due to the positive movements of the arm 19 and 5 any lagging of the parts when the dies engage the member. The marking disks are disposed in substantially the center of the race way for the can ends so that the can end is moved by the arm 19 in between the marking disks, and the dies will engage opposite sides of the can end and impress the identifying mark therein, temporarily moving the can end away from the arm at least to a sufficient extent to prevent any jamming 10 of the parts. It will thus be seen that the can end is marked during its travel to the can end seat at the seaming station from the stack, and this marking of the can end is brought about without in any way retarding 15 the movement of the can ends so that the can ends may be fed positively by a continuously rotating mechanism.

When it is desired to shift from one pair of identifying marks to another, the interlocking member 69 is raised releasing the same from the member 68 which frees the shaft 27. The disks are then turned to bring the locking lugs 72 into the next pair of grooves 71, or the desired pair of grooves 35 71 corresponding to the marking device which it is desired to bring into operation. The grooves 71 are so positioned that, when the lugs 72 are in a pair of grooves, then the pair of marking dies are properly timed so 40 as to engage and mark the can end as it is moved between the dies of the arm or moving member 19. In view of the fact that the gear 67 is twice the circumference of the gear 66, there are twice as many slots 71 as dies 61.

The shaft 27 is connected to the gear 26 in the following manner. Said gear 26 is provided with a sleeve 76 which is freely mounted on the shaft 27. Clamped to the 50 shaft 27 is a collar 77. Said collar is provided with a hardened bearing sleeve 78 formed with a bearing therethrough, and the sleeve 76 has a projecting lug carrying a similar bearing 79. These bearings are 55 formed with openings 80 which are adapted to be brought into line and a pin to be inserted therein. This pin serves as a means for locking the sleeve 76 and thus the gear 26 to the shaft 27. If for any reason the 60 parts of the can end feed should be blocked or clogged by the bending of a can end, the pin in the opening 80 will be sheared off, thus releasing the shaft 27 from operative connection with the main shaft of the machine.

It will be noted from the above description that the can ends are stacked in the stack-holder and supported by the slides. For each cycle of the machine, a can body is fed under the seaming head, and as it passes 70 along the guide-way it operates upon the controlling arm 54 to couple up the lever 44 with the slide 41, and this causes the releasing of a can end from the stack so that said can end will be picked up by the rotating 75 arm 19, moved along the can end race, pass between the marking dies, and then onto the can end seat at the seaming station. The rotating arm or member 19 positively moves the can ends and positively positions the 80 can ends at the seaming station.

It is obvious that minor changes in the details of construction and the arrangement of parts may be made without departing from the spirit of the invention as set forth 85 in the appended claims.

Having thus described our invention, what we claim as new and desire to secure by Letters Patent, is:

1. The combination of a supporting 90 bracket having a can end seat at the seaming station, a stack-holder, a can end race formed in said bracket and leading from the stack-holder to the can end seat, a continuously rotating member adapted to engage the can end at the stack-holder and move the same along said can end race to said can end seat at the seaming station, and rotating marking dies for impressing an identifying mark in the can end as it 95 passes along said can end race and without stopping the movement of the can end.

2. The combination of a supporting bracket having a can end seat at the seaming station, a stack-holder carried by said bracket, a vertically disposed rotating shaft, a rotating member fixed to said shaft and operating to convey the can ends from the stack-holder to the can end seat at the seaming station, an eccentric carried by said vertical shaft, a reciprocating member operated by said eccentric, a lever for releasing the can ends from the stack, and means controlled by the can bodies passing to the seaming station for connecting said lever to said 100 reciprocating member.

3. The combination of a supporting bracket having a can end seat at the seaming station, a stack-holder carried by said bracket, a vertically disposed rotating shaft, 120 a rotating member fixed to said shaft and operating to convey the can ends from the stack-holder to the can end seat at the seaming station, an eccentric carried by said vertical shaft, a sliding member reciprocated by said eccentric, said sliding member having a forked end, a pin connected therewith for guiding the movements of said sliding member, a lever for releasing the can ends from the stack, a spring-pressed pin carried 125 130

- by the sliding member adapted to engage said lever for locking the same to the sliding member, and means controlled by the can bodies as they pass to the seaming station 5 for depressing said spring-pressed pin to cause the sliding member to be locked to the lever.
4. The combination of a supporting bracket having a can end seat at the seaming station, a stack-holder carried by said bracket, a vertically disposed rotating shaft, a rotating member fixed to said shaft and operating to convey the can ends from the stack-holder to the can end seat at the seaming station, an eccentric carried by said vertical shaft, a sliding member reciprocated by said eccentric, said sliding member having a forked end, a pin connected therewith for guiding the movements of said 10 sliding member, a lever for releasing the can ends from the stack, a spring pressed pin carried by the sliding member adapted to engage said lever for locking the same to the sliding member, and means controlled 15 by the can bodies as they pass to the seaming station for depressing said spring pressed pin to cause the sliding member to be locked to the lever, can releasing slides, an oscillating ring for moving said slides in and out, said lever being pivoted to said oscillating ring. 30
5. The combination of a supporting bracket having a can end seat at the seaming station, a stack-holder, a can end race formed in said bracket and leading from the stack-holder to the can end seat, a continuously rotating member adapted to engage the can end at the stack-holder and move the same along said can end race to said can end seat at the seaming station, rotating marking dies for impressing an identifying mark in the can end as it passes along said can end race and without stopping the movement of the can end, and means for rotating the marking dies at a greater speed than the can end feeding member. 35 40 45

In testimony whereof, we affix our signatures.

CHARLES E. BRATT.
GEORGE FLUCK.
